(57) **CLAIM**

We claim the ornamental design for a receiver for a semiautomatic firearm, substantially as shown and described.

DESCRIPTION

FIG. 1 is a top, front, left perspective view of a receiver for a semiautomatic firearm, the view showing the design of the receiver for a semiautomatic firearm;

FIG. 2 is a front elevation view of the receiver for a semiautomatic firearm;

FIG. 3 is a rear elevation view of the receiver for a semiautomatic firearm;

FIG. 4 is a left side elevation view of the receiver for a semiautomatic firearm;

FIG. 5 is a right side elevation view of the receiver for a semiautomatic firearm;

FIG. 6 is a top elevation view of the receiver for a semiautomatic firearm; and,

FIG. 7 is a bottom elevation view of the receiver for a semiautomatic firearm.

The broken lines showing portions of the design in all figures is included for the purpose of illustrating environment and unclaimed features and forms not part of the claimed design.

1 Claim, 4 Drawing Sheets
